UNITED STATES PATENT OFFICE.

WILLIAM MATHEWS NEYLAND, OF GOLIAD, TEXAS.

SUPPORT.

1,409,566.

Specification of Letters Patent. Patented Mar. 14, 1922.

Application filed October 6, 1921. Serial No. 505,833.

To all whom it may concern:

Be it known that I, WILLIAM M. NEYLAND, a citizen of the United States, residing at Goliad, in the county of Goliad and State of 5 Texas, have invented certain new and useful Improvements in Supports; and I do hereby declare the following to be a full, clear, and exact description of the invention, such as will enable others skilled in the art to which 10 it appertains to make and use the same.

This invention relates to new and useful improvements in supports and more particularly to a supporting device attached to the top of a motor vehicle for supporting 15 hats and the like in the top of the vehicle, the main object of the present invention being the provision of a supporting device whereby the supporting elements are attached to the braces or bows of the top of 20 the vehicle and normally arranged, when not in use, parallel with the bow or brace and the main supporting elements adapted to be arranged in spaced parallel relation for 25 engaging the brim of the hat while the crown of the hat is arranged between the main supporting elements.

Another object of the present invention is the provision of a hat supporting device of this character which comprises two parallel 30 supporting elements preferably of a flexible type and adapted to be normally wound upon a spring actuated drums and unwound from said drums and engage hook members for retaining said supporting elements in an extended position whereby they will be arranged in parallel relation for engaging the rim of a hat while the crown is arranged between the supporting elements.

A further object of the invention is the 40 provision of a hat supporting device adapted to be attached to the braces or bows of a motor vehicle top, said device comprising spaced spring actuated drums having yieldable supporting elements wound thereon, 45 said supporting elements being adapted to be extended from the drums and engage hook members to provide spaced parallel supports and it will be apparent that the supporting elements may be extended longitudinally of 50 the bow or braces or be extended transversely between the bows or braces.

With the above and other objects in view, the invention consists in the novel features of construction, combination and arrangements of parts hereinafter more fully set

forth, pointed out in the claims and shown in the accompanying drawings, in which:

Figure 1 is a transverse section through a motor vehicle top showing my improved supporting device attached thereto; 60

Fig. 2 is a plan view looking toward the top of the vehicle;

Fig. 3 is an enlarged side elevation;

Fig. 4 is a plan view illustrating a slightly modified form of the invention; 65

Fig. 5 is a side elevation of that form illustrated in Fig. 4;

Fig. 6 is a plan view illustrating another form of the invention;

Fig. 7 is a side elevation of the form shown 70 in Fig. 6,

Fig. 8 is a plan view of still another form of the invention, and

Fig. 9 is a transverse sectional view 75 through one of the spring drums.

In attaching my improved device to a motor vehicle top, it is preferred to have the entire device attached to one of the cross bows or supporting braces or the spring actuated drums may be attached to one of the 80 cross bows or braces and the supporting elements which are normally wound upon the drums extended from the drums transversely to one of the other bows or braces. In the preferred form of my invention, as illustrated in Figs. 1 to 3 inclusive, the main supporting plate 1 is attached to one of the bows 2 of the top 3 by means of the screws 4 although it will be understood that other suitable fastening means may be used. 85 Mounted upon the plate 1 at each end thereof, are the spring actuated drums 5 upon which the yieldable supporting elements 6 are normally wound. It will be apparent that each of the drums is provided with a 90 casing 7 having a suitable opening through which the supporting elements 6 extend.

In order to retain the supporting members 6 in an extended position, so that they will be arranged in spaced parallel relation as 100 shown in Fig. 2, pivoted arms 8 are provided, said arms being pivotally mounted as at 9 adjacent their inner ends upon the plate 1. These arms are normally disposed in a position nearly parallel with the bow 2 as 105 shown in dotted lines in Fig. 2, but when it is desired to use the arms for retaining the supporting members 6 in an extended position, the arms are swung outwardly to a position transversely or at right angles to the 110

bow 2. In order to retain the arms 8 in their operative or extended position, the inner ends of the arms which project beyond the pivot point 9 engage suitable stops 10 carried by the plate 1 to thus limit the outward movement of the arms.

In arranging the supporting members 6 for use, the loops 11 which are formed at the outer ends of the supporting members 10 are drawn outwardly, unwinding the supporting element from the drum until the loop 11 can be engaged over the hook portion 12 at the outer end of each of the arms 8 as clearly illustrated in Fig. 2, it being understood 15 that the arms 8 are moved to their operative position at right angles to the bow 2. After each of the supporting elements have been extended so that the loops 11 are engaged with the hooks 12 the two supporting elements will be arranged in spaced parallel relation, but due to the arrangement 20 of the arms 8, and the drums 5, these supporting elements as shown in Fig. 2 will be arranged on an oblique angle with respect 25 to the bow 2 as shown in Fig. 2. In order to support a hat in position between the two elements 6, the hat can be first arranged against the plate 1 and each of the supporting elements 6 then unwound from 30 the drum 5 for engaging the loops 11 with the hooks 12, each of the supporting elements being passed upon opposite sides of the crown of the hat so that the rim of the hat will rest upon the two supporting elements 35 as shown in Fig. 2.

When it is desired to remove the hats from between the supporting elements, either one or both of the supporting elements can be detached from the arms 8 by removing the 40 loop 8 from the hook 12, the spring actuated drums re-winding the supporting elements, while the springs 13 which are mounted upon the pivot pins 9 will move the arms 8 to their normal positions as shown in 45 dotted lines in Fig. 2. It will be apparent that the hat supported between the two elements 6 can be removed by disengaging one of the loops 11 from one of the hooks 12, but should it be desired not to use the supporting 50 device for sometime again the other loop 11 can be released so that all of the parts can be returned to their normal positions. It will be apparent that the flexible supporting elements 6 are provided at their outer ends 55 with a stop member 14 which will engage the outer surface of the casing 7 of each drum so as to prevent the loop 11 from passing into the casing 7, the opening through which the flexible supporting elements pass, 60 being duly large enough to permit free movement of the elements through the same and thus preventing the stop member 14 from passing therethrough.

In Figs. 4 and 5 I have illustrated a 65 slightly modified form of the invention

wherein the spring actuated drums and the hook members are arranged in spaced opposed relation, the drums 15 being mounted upon a plate 16 which is pivoted upon the bow 2' and normally disposed in longitudinal parallel relation with the bow 2' as shown in dotted lines in Fig. 4, but when in use is disposed transversely across the bow as shown in full lines. The pivot pin 17 upon which the plate is mounted is provided with a coil spring 18, said spring having one end connected to the plate 16 and the other end connected with the pivot pin so that when the plate is released, it will move to its position in longitudinal alignment 75 with the body 2', the tension of the spring 18 forcing the same to this position and in order to limit the swinging movement of the plate 16, a stop member 19 is provided against which the plate rests when in a 80 normal position.

Arranged in spaced relation with the plate 16 is a pivoted arm 20, said arm being mounted upon the pivot post 21, the pivot post being arranged centrally between the ends 90 of the arm so that when the arm is swung to a transverse operative position as shown in full lines in Fig. 4, the ends of the arm will extend an equal distance beyond the side edges of the bow 2' and the hooks 22 which 95 are formed at the outer ends of the arm will be disposed in alignment with the drums 15 upon the ends of the plate 16 when the plate 16 is moved to a transverse operative position whereby the flexible supporting elements 100 23 may be unwound from the drums and the loops 24 formed at the ends of said flexible elements be engaged with the hooks 22 thus forming two spaced parallel supporting members adapted to engage the rim of a hat 105 as shown in Fig. 4, while the crown of the hat will be disposed between the supporting elements.

Mounted upon the pivot pin 21 is a coil spring 25, one end of which is attached to the arm 20 and the other end attached to the pivot pin 21 whereby when the arm is not in use, the tension of this spring will force the same to its normal position longitudinally of the bow 2' as shown in dotted lines in Fig. 4 and in order to limit the swinging movement of the arm, a stop 26 is provided against which the arm rests to prevent further swinging movement in one direction. Thus, when the device is not in use, the plate 16 carrying the drums 15, and arm 20 will be disposed in longitudinal alignment with the bow 2', but when it is desired to use the supporting elements, the plate 16 is moved to a position transversely of the body 2', the operator then grasps one of the loops 24 and moving the arm 20 transversely of the body 2' engages the loop with one of the hooks 22, the rim of the hat can then be inserted beneath the supporting element 120 125 130

arranged in position and the operator will then grasp the other loop and unwind the supporting element from the other drum, engaging the loop with the hook 22 whereby 5 the plate 16 and the arm 20 will be retained in a transverse position with respect to the bow 2', the supporting elements engaging beneath the rim of the hat and disposed upon opposite sides of the crown. In order to release the hat, the operation may be reversed, 10 removing one of the loops 24 permitting the supporting element to be automatically wound upon the drum and the hat removed from beneath the other supporting element. 15 The other hook is then released and the plate 16 and arm 20 will be moved to a longitudinal position with respect to the bow 2' by means of coil springs 18 and 25. In Figs. 6 and 7, I have illustrated still 20 another form of the invention wherein the hooks and drums are arranged in opposed relation and in order to bring out more specifically the exact relation of the hooks one with the other, as well as the drums, I wish 25 to state that they are arranged in opposed relation on a diagonal line with respect to the support upon which they are mounted, thus one of the drums is arranged in opposed relation with one of the hooks. The bow 2^a 30 has mounted thereon, spaced plates 26 and mounted for swinging movement upon these plates are the arms 27 mounted upon the pivots 28. These pivots 28 have mounted thereon coil springs 29, one end of each being attached to the pivot post 28 and the other end attached to the arm 27 whereby when the arm is not in use, the tension of the coil spring will move the arm to a position longitudinally with respect to the bow 2^a as 35 shown in dotted lines in Fig. 6. Mounted upon one end of the arm is the spring actuated drum 30 carrying the flexible supporting element 31 which is provided with the usual loop 32 at its outer end. The opposite 40 end of the arm 27 is provided with a hook portion 33 adapted to be engaged by the loop of the flexible element carried by the opposing arm.

In Fig. 6 I have illustrated in full lines, a 50 device in an operative position, both of the flexible elements 31 being extended and the loops 32 engaged with the hooks 33 whereby the rim of a hat may be inserted to engage or rest upon the supporting members 55 31. When it is desired to release the hat, the loops 32 will be removed from the hooks 33, the coil springs 29 moving the arms 27 to their inoperative position as shown in dotted lines, the stop members 34 engaging one 60 end of each arm to limit the swinging movement of the same whereby when the device is not in use, the arms 27 will be arranged in longitudinal relation with respect to the bow 2^a.

65 In Fig. 8, I have illustrated another form

of the invention wherein the spring actuated drums 35 are mounted upon the bow *a*, while the hook members 36 which are to be engaged by the loops 37 of the supporting elements 38 carried by the drums 35 are arranged upon the bow *b* which is arranged in spaced parallel relation with the bow *a*, thus the two supporting elements 38 will be extended transversely between the bows *a* and *b* and arranged in spaced parallel relation 70 as indicated in Fig. 8 to provide a suitable support for a hat whereby the hat may be readily inserted between the top of the vehicle and the supporting elements so that the rim will be allowed to rest upon the supporting members 38 and the crown projected between the same. This form of the invention is preferably used when it is desired to extend the supporting elements from one 75 bow or brace to another, the same being extremely simple in its construction as the spring drums 35 are attached in spaced relation to the bow *a* and the hook members 36 will be attached in spaced relation to the bow *b*, each of the hook members being arranged in transverse alignment with its operating drum so that the supporting elements or members 38 can be readily extended and the loops engaged with the hooks 36 80 to provide a suitable support for a hat. 85

90 From the above description taken in connection with the accompanying drawings, it will be readily apparent that I have provided an extremely simple and durable device which can be readily attached to the bow or braces of a motor vehicle top and the supporting elements quickly and easily arranged in position for supporting a hat or the like. The device when not in use is moved to a position entirely out of the way 100 or especially is it arranged in parallel relation with the bow upon which the device is mounted whereby any object coming in contact with the top thereof, will not displace portions of the device. 105

110 I claim:

1. A device of the class described comprising flexible supporting members, spring drums upon which said members are normally wound, engaging members arranged 115 in spaced relation and adapted to be engaged by the outer ends of said flexible supporting elements when unwound from the drums and extended in spaced parallel relation, whereby to retain said supporting elements 120 in an extended position.

2. A supporting device of the class described including spring actuated drums arranged in spaced relation, flexible supporting elements normally wound thereon, hook 125 members arranged in spaced relation and operatively disposed in opposed relation with the drums whereby the flexible supporting elements are unwound from the drum and extended in spaced parallel relation for en- 130

gaging their outer ends with the hook members to provide spaced parallel supports as and for the purpose specified.

3. A device of the class described including a supporting member, spring actuated drums arranged in spaced relation upon said supporting member, hook members pivotally mounted upon the supporting member and normally arranged in substantial alignment with the supporting member, flexible supporting members normally wound upon the drums, means for retaining said hook mem-

bers in their normal positions, said hook members being disposed in transverse relation with respect to the supporting member 15 when in an operative position whereby the flexible supporting members are unwound from the drum to an extended parallel position and engaged with the hook members when in an operative position to provide 20 spaced parallel supports.

In testimony whereof I affix my signature.

WILLIAM MATHEWS NEYLAND.
